UNITED STATES PATENT OFFICE

134,631

DESIGN FOR A TROLLEY WIRE SPLICER

Albert H. Genter, Mount Lebanon Township,
Allegheny County, Pa.

Application March 24, 1942, Serial No. 106,305

Term of patent 14 years

To all whom it may concern:

Be it known that I, Albert H. Genter, a citizen of the United States of America, residing in the township of Mount Lebanon, county of Allegheny, and State of Pennsylvania, have invented a new, original, and ornamental Design for a Trolley Wire Splicer, of which the following is a specification, reference being had to the accompanying drawing, forming a part thereof.

In the drawing Fig. 1 is a top plan view of the

trolley wire splicer; Fig. 2 is a side elevational view of the trolley wire splicer showing my new design; and Fig. 3 is a sectional view taken along the line III—III of Fig. 2.

The opposite side of the device is the same as that shown.

I claim:

The ornamental design for a trolley wire splicer, as shown and described.

ALBERT H. GENTER.
